FLUSH BOX MECHANISM

George H. Sprague, East Northport, N. Y., assignor of one-half to Lillian A. Moir, East Newport, N. Y.; Lillian Moir Sprague, executrix of said George H. Sprague, deceased, assignor to Lillian Moir Sprague, Commack, N. Y.

Application June 21, 1944, Serial No. 541,419

2 Claims. (Cl. 4-67)

1

This invention relates to a flush box mechanism and more particularly to a mechanism adapted for use with the flush boxes of toilets.

A primary object of this invention is the provision of a flush box mechanism of improved and simplified construction embodying relatively few operating parts.

A further object is the provision of an improved means for securing certain parts of such a mechanism in related assembly which may be readily released to permit replacement of certain other parts without the necessity of disassembling the entire device.

A more specific object is the provision of an improved split clamp holding the operating rod of the flush mechanism in desired positions.

A still further object is the provision of an improved means of securing a ball valve to an operating device in order to reduce the wear on such a valve to a minimum.

Other objects will in part be obvious and in part pointed out hereinafter.

Having reference now to the accompanying drawings wherein there is shown a preferred form of this inventive concept,

Figure 1 is a side elevational view of a toilet flush box, certain parts thereof being broken away and certain parts shown in section to show the positioning of the operating mechanisms of the instant invention.

Figure 2 is a top elevational view of the toilet box cover of Figure 1, certain underlying parts being shown in dotted lines.

Figure 3 is an enlarged side elevational view of a portion of the mechanism shown in Figure 1.

Figure 4 is a side sectional view through a portion of the ball valve mechanism comprising a part of the instant invention.

Figure 5 is a perspective view of a clamping device comprising a detail of this invention.

Figure 6 is an enlarged perspective view of the lever mechanism shown in Figure 1, and

Figure 7 is an enlarged detail view of the detachable connection between certain operating elements of the structure.

Like reference numerals refer to like parts throughout the several views of the drawings.

Having particular reference now to the drawings, and Figure 1 thereof, 10 designates a flush box for toilets, and may be constructed of any suitable material such as porcelain. Box 10 is provided with a cover or lid 11 of any suitable material such as porcelain or wood and is provided on its inner surface with a plurality of extending lugs 12 adapted to hold the cover in

2

aligned position when placed on the flush box. Flush box 10 is provided with the customary inlet pipe 13, outlet pipe 14, and overflow pipe 15. Secured to the underside of cover 11 is a mounting bracket 16 adapted to support a bellcrank lever generally indicated at 17. As best shown in Figure 6, lever 17 is comprised of an extending portion 18 terminating in a flat end, a lug 19 extending upwardly therefrom and having an aperture 20 therethrough and an opposite end portion 21 extending at an angle with respect to portion 18, and provided with an aperture 22 adjacent the extremity thereof. As best shown in Figure 1, lever 17 is adapted to be mounted in bracket 16 for pivotal movement and is secured in position as by a rivet or pin 23. Cover 11 has a suitable hole bored therethrough at a point adjacent flat end 18 of lever 17, through which is passed a rod 25 having at its outer extremity a push button 26 and having positioned on its lower extremity, subsequent to its insertion in the hole, a collar 27 designed to preclude the withdrawal of the same from the hole. Details of this construction are best disclosed in Figure 15. As best shown in Figure 7, a hook 30 terminating in a loop 31 is secured in aperture 22 of portion 21 of lever 17. Hook 30 is adapted detachably to engage a loop 32 comprising the upper end of an operating rod 33. As best shown in Figure 30, the lower end of rod 33 terminates in a threaded portion 34 and has threaded thereon an outside adjusting nut 35. Positioned beneath nut 35 is an outside washer 36, adapted to abut the upper surface of a conventional hollow rubber ball-type valve closure member 37. Also, positioned on end 34 of rod 33 but within ball valve closure 37 is a second or inside washer 38, adapted to engage the inner surface of valve closure 37 and secured in position by a second or inside 40 clamping nut 39. The construction immediately above described materially strengthens the securing of valve closure 37 to rod 33 and reduces the possibility of tearing the relatively thin rubber of closure 37. In order to facilitate assembly and insertion of the clamping nut 39 and inside washer 38 an opening 37a is provided in the hollow ball valve 37 opposite the rod end 33. A guide member and clamp for rod 33 is generally indicated at 40. Guide member 40 is comprised of a one piece clamp formed of a double bent plate having a relatively large cylindrical portion 41, adapted to be adjustably positioned up and down and clamped about the overflow pipe 15 to limit the axial movement of the rod 33 with the valve 37, a pair of flat extending

members 42 terminating in a split cylindrical portion 43, comprised of two semi-cylindrical portions formed at the ends of flat portions 42. Screws 44 having flat heads engage suitable threaded apertures in the two flat portions 42 and serve to hold the guide member in clamped position on the pipe 13. Thus it will be seen that cylindrical portion 43 is adapted to surround and serve as a guide for rod 33 and that upon releasing of screws 44 from engagement with their associated threaded apertures, cylindrical portion 43 may be separated to permit removal of rod 33 therefrom for a purpose to be described hereinafter, without the necessity of removing the clamp as a unit from the overflow pipe.

From the foregoing the operation of the device should now be readily understood by those skilled in the art. If it becomes necessary to replace valve closure member 37, which, it may be pointed out, is the portion of the device most subject to wear, the operation is as follows: Lid 11 is first raised a short distance from box 10 (such movement being permitted by the distance between the top of member 37 and member 40). Hook 30 is then disengaged from loop 32 and the top 11 removed completely. Screws 44 are then loosened and clamp member 40 separated to a degree sufficient to permit the removal of rod 33 laterally from cylindrical portion 43 of clamp 40. Rod 33 and associated member 37 are then removed from box 10 and nut 39 and washer 38 then removed from end 34 of rod 33 through the opening 37a. The rubber ball valve closure member 37 may then be removed from rod 33 and a new member substituted therefor, washer 38 and nut 39 then being replaced. The closure member and rod are then replaced in position and guide member 43 positioned thereabout and screws 44 tightened to hold the parts in related assembly. Cover 11 is then replaced but an opening of sufficient size to permit the insertion of a hand is left between cover 11 and the top of box 10, and hook 30 reengaged with loop 32. Upon complete closure of cover 11, the operating mechanism is now in position for operation.

From the foregoing it will now be seen that there is herein provided a device embodying all the objects of this invention and many others including many advantages of great practical utility and commercial importance. It will also be seen that the construction herein disclosed provides a flush valve operating mechanism which is reliable in operation, sturdy and durable in construction, and comprised of a relatively small number of operating parts, the whole being so designed and arranged as to produce a minimum of strain and wear on the operating parts thereof, and to permit ready replacement of such parts as become worn or otherwise inoperative.

As many embodiments may be made of this

inventive concept and as many modifications may be made in the embodiment hereinbefore described and shown in the accompanying drawings, it is to be understood that all matter herein is to be interpreted merely as illustrative and not in a limiting sense.

I claim:

1. In a flush box having a tank, a discharge pipe therefrom, a flush valve controlling said discharge pipe and a guide means for the stem of said flush valve, in combination, a removable cover for said tank and a flush valve operating mechanism supported by and removable with said cover, said mechanism comprising a lever pivoted intermediate its ends to the under surface of said cover, a detachable, swiveling connection between one end of said lever and said flush valve stem and an actuating push button extending through said cover and engaging the other end of said lever, said push button having an enlarged portion thereon preventing withdrawal of the same through said cover.
2. In a flush box having a tank, a discharge pipe therefrom, a flush valve controlling said discharge pipe and a guide means for the stem of said flush valve in combination, a removable cover for said tank and a flush valve operating mechanism supported by and removable with said cover, said mechanism comprising a lever pivoted intermediate its ends to the under surface of said cover, a detachable, swiveling connection between one end of said lever and said flush valve stem and an actuating push button extending through said cover and engaging the other end of said lever, said push button having an enlarged portion thereon preventing withdrawal of the same through said cover, said swiveling connection providing sufficient lost motion for raising said cover to effect attachment and disengagement of said connection with said stem.

GEORGE H. SPRAGUE.
